UNITED STATES PATENT OFFICE.

MARTIN E. EVANS, OF PITTSBURGH, PENNSYLVANIA.

LOCKING-TONGUE FOR FENCEPOSTS, &c.

1,315,220.

Specification of Letters Patent. Patented Sept. 9, 1919.

Application filed December 31, 1918. Serial No. 269,136.

To all whom it may concern:

Be it known that I, MARTIN E. EVANS, a resident of Pittsburgh, in the county of Allegheny and State of Pennsylvania, have invented a new and useful Improvement in Locking-Tongues for Fenceposts, &c., of which the following is a specification.

This invention relates to metallic fence posts and other supports and spacing members, such, for instance, as used for concrete reinforcement, to support metallic lathing, shingles, and the like.

The object of the invention is to provide a metallic post or other support with punched out tongues, integral at one end with the post or other support, for fastening and spacing the wires and other members to be secured to the post or support, and which tongues are formed with means to enter and lock the free end of the tongue in a tongue slot, thereby forming in effect a staple which is an integral part of the post or support and which provides a stronger fastener and one not so liable to break, as such tongues heretofore formed. A further object is to provide tongues of such form that their free ends can be interlocked in tongue slots by the use of ordinary tools, or even by a hammer alone, by an ordinary workman.

As the invention is particularly adapted for plate metal fence posts, it is illustrated and described in connection with this particular use, but it will be understood that the invention is not limited to this particular use, but is adapted for any of the various uses above specified.

In the accompanying drawing Figure 1 illustrates a wire fence post embodying one form of the invention; Fig. 2 is an elevation of a portion of the post showing one form of locking tongue; Figs. 3 and 4 are vertical sectional views of the post showing the tongue both before and after being locked in position; Fig. 5 is an elevation of a portion of a fence post showing a modified form of the invention; and Figs. 6 and 7 are vertical sectional views of the post showing modified ways of utilizing the locking tongue.

In all of the views of the drawing 1 indicates a metallic fence post and 2 the wires secured thereto. Such posts are formed of thin plate metal, bent either to tubular form, forming a so-called "closed" post, or to U or concave form, forming a so-called "open" post. The tongues for fastening the wires

to the post are indicated by the reference numeral 3, the same being punched out of the plate metal, being integral with the plate metal at one of their ends and bent outwardly from the body of the plate to permit of insertion of the wires between the same and the outer face of the post, and which tongues, in all forms are so formed that their free ends can enter and be interlocked in a tongue slot, the slot formed either by punching out the particular tongue under consideration, or the slot formed by punching out an adjacent tongue.

These tongues are preferably punched out while the plate is in the flat, and since they extend lengthwise of the post, the curving of the plate transversely to the tubular or U-shape, narrows these slots somewhat on the inner face of the plate, so that they are no longer of the full width of the tongues punched therefrom. Consequently if the end of a tongue is forced back through the slot from which it was punched, any enlargement on the tongue will interlock behind the side walls of the slot. This principle is utilized in the various forms of tongues illustrated.

In the form shown in Figs. 1, 2, 3, and 4 the tongue 3 is provided with a narrow portion 4, below its end or head portion 5. With this form, after the wire 2 is inserted, the end of the tongue is bent down until its head can enter through the under portion 6 of the slot, just below the narrow portion 4^a, then forced therethrough, as shown in Fig. 3. This can be done by merely tapping the tongue with a hammer to first bend it and then force its head through the slot. The free end of the tongue is then lifted slightly, by a suitable tool or by lifting on the wire 2, thereby bringing its head 5 behind the edges of the narrow slot portion 4^a, and forming the interlock, as shown in Fig. 4.

Fig. 5 shows a modification in which the tongue 3 is provided with serrated or saw-toothed edges, thus providing a plurality of small lateral projections separated by small narrower portions. The base of the tongue, and of the slot formed by punching it out, is wider than any of the lateral projections so that said tongue can be inserted through the base of the slot, in the same manner as shown in Fig. 3, and then lifted up to interlock some one pair of its lateral projections behind the wall of the upper portion of the

slot. This form allows for a certain amount of variation as to the final position of the tongue.

In Figs. 6 and 7 the free end of the tongue, instead of being interlocked with the slot from which it is punched, is interlocked with the slot immediately below it, Fig. 6 showing the tongue bent downwardly on the outside of the post and Fig. 7 showing the tongue bent downwardly on the inside of the post. This method of using the tongue is possible where the slots are close to each other longitudinally of the post or other support. With these embodiments the head of the tongue is entered through the wide or T portion of the slot immediately below, and its end then forced downwardly until this T head is behind the walls at the sides of the lower narrower portion of said slot.

20 All forms of tongues described can be moved to final position by first giving an initial sharp bend to bring their ends into the wide portions of the slots which they are to enter, and then by properly tapping the tongues with a hammer they can be caused to bend to the desired final position.

Various other modifications obviously can be made in the form of the interlocking tongue. With all forms described the tongue is integral at one end with the metal of the post or other support, and said tongue is so formed that its free end is entered into and interlocked in a tongue slot, thus forming in effect a staple which furnishes a strong support for the wire or other member to be fastened to the post or support and throwing any strains which may be brought upon the wire upon both ends of the tongue. As a consequence these tongues are stronger and not as liable to break, as with tongues as heretofore used, in which the free end of the tongue was not interlocked with the post, and as a consequence the entire strain was thrown upon the root of the tongue, thus resulting in frequent breakage.

The post or similar member described can be fabricated by punching the tongues from

the plate metal while in the flat, with ordinary gang punching machinery, either rotary or reciprocatory, or combined rotary and reciprocatory. The dies for punching the tongues from the flat will also be so formed as to bend the tongues outwardly to one side of the body of the plate. Or the tongues can be left in normal position, the necessary bending being effected by the erector. All of the operations of manufacture are simple, and add nothing to the cost of manufacturing similar articles with integral tongues.

60 I claim:

1. A plate metal post or spacing member, provided with locking tongues punched from the metal of said member without removing metal therefrom, thereby forming complementary slots, said tongues and slots being wide at their free ends and narrower at their intermediate portions and again wider at their bases, the base portions being at least as wide as the free end portions, whereby a tongue can be entered into and locked in its slot without twisting, by entering its wide end portion through the widened base portion of the slot and moving the end of said tongue to bring its widened portion behind the narrower portion of the slot.

2. A plate metal post or spacing member of curved form, provided with locking tongues punched from the metal of said member and extending lengthwise thereof, said tongues and slots being wide at their free ends and narrower intermediate their ends and the slots adjacent their bases being widened, whereby a tongue can be entered into and locked in a slot without twisting by entering its widened end portion through the widened base portion of a slot and moving the end of the tongue to bring its widened portion behind the narrower portion of the slot.

90 In testimony whereof, I have hereunto set my hand.

MARTIN E. EVANS.
